ALBERT COWELL, OF KIDDERMINSTER, ENGLAND, ASSIGNOR TO JAMES HUMPHRIES & SONS, OF SAME PLACE.

Design No. 5,021, dated June 20, 1871.

DESIGN FOR CARPET.

The Schedule referred to in these Letters Patent and making part of the same.

To all whom it may concern:

Be it known that I, ALBERT COWELL, of Kidderminster, Worcestershire, in England, have invented a new and original Design for Carpets; and I do hereby declare that the following is a full, clear, and exact description thereof, which will enable others skilled in the art to make and use the same, reference being had to the accompanying photographic illustration forming part of the specification.

The nature of my design is fully represented in the accompanying photographic illustration, to which reference is made.

I claim as my invention—

The design for carpets, as shown.

ALBERT COWELL.
